Inventor
August Kahr,
By Henry Mattox Atty.

UNITED STATES PATENT OFFICE.

AUGUST KAHR, OF LEIPZIG-LINDENAU, GERMANY.

APPARATUS FOR THE MANUFACTURE OF HOLLOW BRICKS CLOSED ON ALL SIDES.

1,411,170.

Specification of Letters Patent. Patented Mar. 28, 1922.

Application filed May 17, 1920. Serial No. 381,951.

To all whom it may concern:

Be it known that I, Dr. AUGUST KAHR, engineer, a subject of the German State, and resident of Leipzig-Lindenau, Germany, have invented certain new and useful Improvements in Apparatus for the Manufacture of Hollow Bricks Closed on all Sides, (for which application has been filed in Germany June 10, 1913; Switzerland Dec. 10, 1919; Sweden Dec. 10, 1919; Holland Dec. 13, 1919; Norway Dec. 16, 1919; Denmark Dec. 17, 1919; Italy Dec. 27, 1919; Spain Feb. 10, 1920; Belgium Feb. 24, 1920; France Feb. 26, 1920); and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

There are already brick-presses for the manufacture of hollow bricks closed on all sides. This press has in its mouth-piece a core that may be turned. This core was hitherto of such shape that it pushed at its rotation a quantity of clay into the cavity made by itself and formed in this manner the closing wall.

Besides the brick-press is provided with a contrivance as to avoid the formation of a vacuum. This contrivance usually consisted of a tongue (prickle) which made a hole in the front-wall of the brick so that air could enter the interior of the hollow brick from outside through the formed front-wall.

As to avoiding the vacuum all the brick-presses for the manufacture of hollow bricks closed on all sides operate in the same way, without any difference whether the manufacture of the brick ensued by discharging the core from the vertical to the horizontal position or by drawing back the core from the mouth-piece or by damming up the clay mass by means of slide-valves (bolts). In all these cases it was necessary to make holes in the closing walls of the hollow brick to give access to the air into the interior of the brick.

On account of these holes in the closing walls the bricks made in this way were only to be used as quarry-stones for spandrel, however, they could not be used where a

smooth surface was wanted, e. g., for fire-proof gables or as brick for facing etc.

According to the invention the brick-presses for the manufacture of hollow bricks closed on all sides and supplied with a revolving core shall be modified as to make bricks which are completely closed at its shutting walls, that is to say without air-openings. The process is also applicable to quarry-stones, especially if less plastic clay is used.

The essential features of the invention is to introduce air from outside into the hollow space that is made, in the out-going-direction of the clay-string at the place where the hollow space is formed, i. e., directly at the core. For this manner of air-supply those presses suit best which have a revolving core remaining at its rotation always in the mouth-piece.

The supply of air is done by air-chambers which may be placed in the core or the latter is divided and a special air-chamber having an additional piece is used, whereby the chamber is as narrow as possible and placed between the two parts of the core.

In order to allow the escape of gas and steam afterwards during firing, air-holes may be pricked in the sides of the clay string on the non-facing sides of the tile.

Both methods of supplying air can be combined, and also it is possible to use a vertical shaft instead of a horizontal one, particularly when several cores are arranged one over the other.

In the drawings, in which like parts are similarly designated—

Figure 1 is a cross section, and

Fig. 2 is a longitudinal section of one form of mechanism for producing completely closed hollow tile.

Fig. 3 is a cross section, and

Fig. 4 is a longitudinal section of another form of mechanism.

Fig. 5 is a perspective view illustrating one end of the clay string.

Fig. 6 is a longitudinal section showing the method of forming the end walls.

Figs. 7 to 11 illustrate the successive stages of formation of the partition.

The core placed in the mouth-piece through which the plastic is forced over the core, which is generally of a cylindrical form and has an exterior recess σ which brings forward the clay-mass for the formation of the

closing wall at each rotation. The core is hollow and consists of two or several parts *d*, *e*, which are suitably screwed together. The part *d* may be taken off in order to clean 5 the inner parts of the core. One part of the core rotates with the shaft *c* through which the air enters.

The air passes out through the hole *f* directly into the hollow space in the clay 10 string, in advance of the clay forwarded by the depression *o*. In Figures 3, 2, 4 the air is lead through a special tube *d* into the air-chamber *g*. The core consists of two parts 15 *b*¹, *b*², situated by the side of the air chamber. The shaft *c* in this case is solid and passes through the air-chamber. The exit 20 of the air ensues either through the hole *i* or through a slit in the air-chamber and in both cases automatically, caused by the arising vacuum.

The air, however, may be pressed in from outside by air-pumps but the pressure is not high, as otherwise the sides of the string would bulge.

25 Figure 5 shows the completely closed wall of a brick. Figure 6 is a working-scheme with the revolving core. The separation of the bricks is made by cutting the clay-string on the line *m*—*n*.

30 I claim—

1. In a continuous hollow brick or tile making machine, the combination with a mouth-piece through which clay is expressed; of a cylindrical rotatable core having a clay forwarding recess in its periphery and having means to conduct air to the interior of the clay string during the rotation of said core.

2. In a continuous hollow brick or tile making machine, the combination with a 40 mouth-piece through which clay is expressed; of a cylindrical core having a clay forwarding recess in its periphery, said core composed of a plurality of hollow sections, 45 one of which has one or more discharge ori- fices for discharging air into the interior of the clay string during the expression thereof.

3. In a continuous hollow brick or tile making machine, the combination with a 50 mouth-piece through which the clay is expressed; of a cylindrical core composed of one or more hollow members, a hollow shaft for rotating said core, said core having a clay-forwarding depression extending longitudinally thereof, and perforations in the portion of the core that is not depressed for supplying air to the interior of the hollow string.

4. In a continuous hollow brick or tile 60 making machine, the combination with a mouth-piece through which the clay is expressed; of a cylindrical rotatable core member having a clay forwarding recess in its periphery consisting of two portions, and a 65 hollow stationary member between said portions having air exits for discharging air into the interior of the clay string.

In testimony that I claim the foregoing as my invention, I have signed my name in 70 presence of two subscribing witnesses.

DR. AUGUST KAHR.
